US0D1078389S

(12) **United States Design Patent** (10) Patent No.: **US D1,078,389 S**
(45) Date of Patent: ** Jun. 10, 2025

(54) **DRINKING GLASS**

(71) Applicant: **TURKIYE SISE VE CAM FABRIKALARI ANONIM SIRKETI**, Istanbul (TR)

(72) Inventor: **Ekin Sayar**, Istanbul (TR)

(73) Assignee: **TURKIYE SISE VE CAM FABRIKALARI ANONIM SIRKETI**, Istanbul (TR)

(**) Term: **15 Years**

(21) Appl. No.: **35/519,377**

(22) Filed: **Nov. 9, 2023**

(80) **Hague Agreement Data**

Int. Filing Date: **Nov. 9, 2023**

Int. Reg. No.: **DM/233644**

Int. Reg. Date: **Nov. 9, 2023**

Int. Reg. Pub. Date: **Dec. 15, 2023**

(30) **Foreign Application Priority Data**

Jun. 2, 2023 (TR) 2023/005560

(51) LOC (15) Cl. **07-01**

(52) U.S. Cl.

USPC **D7/523**
